UNITED STATES PATENT OFFICE

2,582,607

MOWER TEETH SHARPENER

August W. Rinne, Steinauer, Nebr.

Application December 28, 1949, Serial No. 135,353

2 Claims. (Cl. 51—33)

1

This invention relates to power actuated grinding machines of the type used for sharpening tools. More particularly it is an object of this invention to provide means for sharpening the blades of a mower without removing the blades from the cutter bar of the mower.

The cutter bar or sickle element of mowers, binders and the like travels comparatively close to the ground where it strikes stones, small stumps and other objects, so that it is subjected to considerable abuse, and therefore the blades or sections thereof require sharpening comparatively often. The blades are riveted to the bar and in removing the blades for sharpening it is necessary to cut the rivets with a chisel driven by a hammer blow, and the blow of the hammer often breaks the blades.

It is, therefore, an object of this invention to provide a V-shaped grinding wheel adapted to enter the opening between two blades of a sickle bar and in combination with means for actuating the grinding wheel and in combination with other means for moving the sickle bar into position for grinding the adjacent sides of a pair of teeth on the cutter bar, the construction being such that the wheel enters the opening between each pair of blades and grinds the cutting edges thereof.

Another object of the invention is to provide a guide rail for slidably and pivotally supporting a bracket for a mower cutter bar.

Still another object is to provide a device as described, the bracket member of which has means for readily securing a cutter bar thereto and also has a detent means for stopping the forward movement of the bracket on its pivotal mounting.

Further objects of the invention are to provide a device as described having the grinding wheel thereto pivotally mounted for controlling the amount of grinding to be done; and having means for holding the wheel away from the cutting bar in a retracted position when not in use.

Yet another object of the invention is to provide a device for the purposes described which is sturdy and durable in construction, reliable and efficient in operation, and relatively simple and inexpensive to manufacture, assemble and utilize.

Other and still further objects and advantages of the invention will become apparent from the following detailed description of a preferred embodiment thereof.

In the drawings:

Figure 1 is a top plan view of the new device having certain portions thereof broken away for convenience of illustrations.

2

Figure 2 is a side elevation of the new device, attached to a portion of a work bench and having the cutter bar and the grinding wheel positioned for grinding.

Figure 3 is a frontal elevation of the device with the cutter blade not shown; certain other portions being broken away for convenience of illustration.

The sharpener of this invention includes a platform or stand 10 having oppositely disposed downwardly extending side walls or rails 12 and 14. As best shown in Figure 2, the platform 10 is secured to a bench 16 by one or more bolt and nut assemblies 18.

As seen in Figure 3, rails 12 and 14 support two downwardly extending spaced apart parallel arms or posts 20 and 22 which are held apart by a support bar 24 for purposes later described.

A main body or lever portion 26 which provides a swinging frame is provided having two spaced apart parallel rails of channel iron of L shape in cross section, having top portions 28 and 30 and side portions 32 and 34 respectively, and being held apart by two metal straps 36 and 38 suitably attached to the undersurfaces of the portions 28 and 30 at the ends of the latter.

Two apertures are provided at the rearward ends of the side portions 32 and 34 in axial alignment with each other. Two like apertures are provided in the sides 12 and 14 for receiving therethrough pivot bolts 40 for pivotally attaching the main body portion 26 to the platform 10.

A handle 42 is suitably attached at its rearward end to the portion 28 by bolts 44, and the handle extends upwardly and forwardly any desired distance for obtaining a substantial amount of leverage to move the main body portion downwardly to the position shown in Figure 2.

A control arm 46 is attached to the portion 30 and is secured at its forward end portion by bolts 48 to the top channel iron portion 30 and extends upwardly and rearwardly therefrom. The extreme rearward end portion 50 is then bent downwardly into approximate parallelism with the platform 10 for receiving therethrough a threaded eye-bolt 52.

A nut 54 is threadedly secured to the eye-bolt 52 on the upper end thereof for adjusting purposes later described.

The eye 56 of the eye-bolt 52 has a hook 58 of the coil spring 60 disposed therethrough. The opposite end of the spring 60 is provided with a like hook 62 received through the eye of an eye-bolt 64 anchored to the platform 10 directly below the eye-bolt 52 as best seen in Figure 2.

The nut 54 can be turned in a proper direction for causing the distance between the eye 56 and the bolt 64 to be lengthened; the spring 60 then pulls downwardly on the arm 46 causing the lever portion 26 to move in the direction of the arrow A, to a retracted position.

The upward movement of the lever portion 26 is restricted by a detent bolt 68, best seen in Figure 3, suitably attached to the platform 10 at the forward end thereof and extending upwardly through an elongated opening 70 in the portion 30 of the main body portion 26. The head of the bolt 68 is larger than the width of the opening 70 for preventing the lever portion 26 from being pulled upwardly past the head of the detent bolt 68.

Two pillow blocks 74 and 76 are located at the forward end and outer edges of the main body portion 26 and are suitably attached to the members 28 and 30 respectively by means of bolts 78. The pillow blocks are in axial alignment for rotatably supporting a shaft 80. The outer end portions 82 and 84 of the shaft 80 are provided with threads thereon for purposes later described.

A pulley wheel 86 is attached to the end portion 84 of the shaft 80 adjacent, but not touching, the side 32 of the main body portion 26.

A grinding wheel 88, having a V shaped outer surface is disposed on the end portion 84 against the outer surface of the pulley wheel 86. A locking washer 90 and a nut 92 hold the grinding wheel 88 rigidly to the shaft 80.

A lock disk 94 is threadedly attached to the end portion 82 against the bearing 74 and is held in place by a nut 96.

A support bracket or shelf 100, approximately Z shaped in cross section is disposed against the arms 20 and 22. The support 100 has a downwardly extending portion 102, having at least two apertures. The arms 20 and 22 of the new device have corresponding apertures for receiving bolts 104 to attach the support member 100 to the arms 20 and 22.

Parallel to, and forwardly of the portion 102 is an upwardly extending bracket portion 104 for slidably and pivotally mounting a bar guide 106.

The bar guide 106 is composed of a piece of angle iron having side arms 108 and 110. Spaced equidistantly along the rearward surface of the arm 108 and attached thereto are a plurality of L-shaped members 112. The upper end portions 114 of the L-shaped members 112 are pointed for purposes later described. The lower end portions 116 of the members 112 are bent rearwardly forming V shaped openings 118 between the lower end portions 116 and detent straps 120 disposed on the opposite side of the arm 108 in alignment with the members 112.

Bolts 122 are disposed through the straps 120, the arm 108, and the members 112 for attaching said members 112 and straps 120 to the arm 108.

Attached to the upper surface of the arm 110 by means of bolts 126 are a plurality of spaced apart angle iron braces 124. An end 128 of each brace 124 is turned upwardly in parallelism with the upper end portion 114 of a member 112. Openings are formed between the ends or guides 128 and upper end portions or guides 114 for receiving a cutter bar 130 having a plurality of teeth 132.

The shaft 80 is rotated by means of a driven belt 140 shown in dotted lines in Figure 1. The cutter bar 130 can be moved endwise into a

5

proper position with respect to the grinding wheel 88. The handle 42 is moved downwardly causing grinding of the mower teeth 132. This operation is then repeated until all of the teeth are ground to a desired sharpness.

From the foregoing description it is thought to be obvious that a mower teeth sharpener constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention except as claimed.

I claim:

1. In a cutter bar blade sharpener, the combination which comprises a horizontally disposed platform having side rails adapted to be positioned on the upper surface of a work bench and having vertically disposed posts on the outer ends of said rails, a vertically swinging horizontally disposed frame positioned above the platform and also having spaced side rails, means pivotally attaching the side rails of the frame to the side rails of the platform providing the vertical swinging action of the frame, an upwardly inclined arm carried by the frame, a spring connecting the extended end of the arm to the platform, a shaft journaled on the said swinging frame, a grinding wheel having a V-shape peripheral surface carried by the shaft, a shelf mounted on the said posts, extended outwardly therefrom, and positioned parallel to the axis of the said shaft, an angle iron bar guide having two arms and mounted on the outer edge of the shelf and positioned with one arm inclined upwardly and inwardly from the outer edge of the shelf, and spaced guide members extended upwardly and inwardly from the said bar guide, said guide members being spaced to receive a cutter bar and positioned whereby cutting edges of blades carried by the cutter bar are inclined inwardly for engagement with the grinding wheel.

2. In a cutter bar blade sharpener, the combination which comprises a horizontally disposed platform having side rails adapted to be positioned on the upper surface of a work bench and having vertically disposed posts on the outer ends of said rails, a vertically swinging horizontally disposed frame positioned above the platform and also having spaced side rails, means pivotally attaching the side rails of the frame to the side rails of the platform providing the vertical swinging mounting of the frame, an upwardly inclined arm carried by and extended from the inner end of the frame, a spring connecting the extended end of the arm to the platform, a shaft journaled on the said swinging frame, a grinding wheel having a V-shape peripheral surface carried by the shaft, a pulley on the said shaft, an elongated shelf Z-shape in cross section mounted on the said posts and positioned parallel to the axis of the said shaft, said shelf having an upwardly extended flange on the outer edge, an angle iron bar guide positioned on the flange on the outer edge of the shelf and having two arms and one of the arms being upwardly and inwardly inclined, spaced guides positioned on the inclined arm of the bar guide for retaining a cutter bar with blades thereon positioned to engage the grinding wheel, one of said guides having

tapering sides providing a point for positioning the blades in registering relation with the grinding wheel, and a handle extended from the swinging frame whereby the frame is drawn downwardly to bring the grinding wheel into engagement with the blades.
